CLAIM

The ornamental design for a security light, as shown and described.

DESCRIPTION

FIG. 1 is a front perspective view of a security light design; FIG. 2 is a rear perspective view of the security light design of FIG. 1;

FIG. 3 is a front view of the security light design of FIG. 1; FIG. 4 is a rear view of the security light design of FIG. 1; FIG. 5 is a left side view of the security light design of FIG. 1;

FIG. 6 is a right side view of the security light design of FIG. 1;

FIG. 7 is a top view of the security light design of FIG. 1; and,

FIG. 8 is a bottom view of the security light design of FIG. 1.

In the drawings, the broken lines depict environmental subject matter that forms no part of the claimed design.
